UNITED STATES PATENT AND TRADEMARK OFFICE
Certificate

Patent No. D. 447,149

Patented: August 28, 2001

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Mike L. Davis, Jackson, TN; Dave C. Smith, Jackson, TN; David W. Robenalt, Jackson, TN; Robert F. Burkholder, Jackson, TN; Fred M. Morgan, Jackson, TN; and Crandall B. Barbour, Jackson, TN.

Signed and Sealed this Eighth Day of July 2003.

LOUIS ZARFUS
Supervisory Patent Examiner
